CLAIM

The ornamental design for loop cutter, as shown and described.

DESCRIPTION

FIG. 1 is a front view of the loop cutter of the invention.

FIG. 2 is a rear view of the loop cutter of FIG. 1.

FIG. 3 is a top plan view of the loop cutter of FIG. 1.

FIG. 4 is a bottom plan view of the loop cutter of FIG. 1.

FIG. 5 is a right side view of the loop cutter of FIG. 1; and, FIG. 6 is a left side view of the loop cutter of FIG. 1.
